UNITED STATES PATENT OFFICE.

EDMOND W. T. RICHMOND, OF ROMFORD, ENGLAND.

DESIGN FOR A GAS-STOVE.

SPECIFICATION forming part of Design No. 33,872, dated January 8, 1901.

Application filed December 11, 1900. Serial No. 39,552. Term of patent 7 years.

To all whom it may concern.

Be it known that I, EDMOND WALTER TYRRELL RICHMOND, a subject of the Queen of Great Britain, residing in Summercourt, Romford, in the county of Essex, England, have invented and produced a new and original Design for Gas-Stoves, of which the following is a specification.

The accompanying drawing shows a perspective view of a gas-stove embodying my design.

The leading features of my design consist of the skeleton standards A, supporting a plain flat table B, which in turn supports a frame C, across the top of which are arranged

a series of parallel bars D, having wavy upper edges. Below the table B is a rectangular shelf E, having a plain flat top. At one side of the frame C and above the table is an oblong coupling F, above which are a series 20 of cock-handles G.

I claim—

The design for a gas-stove, substantially as herein shown and described.

In testimony whereof I have hereunto sub- 25 scribed my name.

EDMOND W. T. RICHMOND.
